UNITED STATES PATENT OFFICE.

GEORGE ALVAH N. COPPEDGE, OF WINSTON-SALEM, NORTH CAROLINA.

ADVERTISING-CALENDAR.

1,285,442.

Specification of Letters Patent. Patented July 31, 1917.

Application filed October 13, 1916. Serial No. 125,424.

To all whom it may concern:

Be it known that I, GEORGE ALVAH N. COPPEDGE, a citizen of the United States, residing at Winston-Salem, in the county of 5 Forsyth and State of North Carolina, have invented a new and useful Advertising-Calendar, of which the following is a specification.

This invention has reference to advertising 10 calendars and is designed to provide a structure capable of displaying advertisements and at the same time indicating the month and day of the month, the calendar feature being of the perpetual type.

15 In accordance with the present invention there is provided a box or casing with mechanism whereby a monthly calendar may be displayed and also providing space for advertisements, the mechanism being so arranged 20 that the year, the month, and the days of the month may be readily changed as needed. The mechanism includes means whereby the names of the months may be changed and the monthly calendar of days 25 may be changed by providing accessible parts ordinarily hidden but readily reached.

Provision is also made for the changing of the advertisements from time to time if such be desirable.

30 The invention will be best understood from a consideration of the following detailed description, taken in connection with the accompanying drawings forming part of this specification, with the further understanding that while the drawings show a 35 practical form of the invention the latter is not confined to any strict conformity with the showing of the drawings, but may be changed and modified so long as such 40 changes and modifications come within the scope of the appended claims.

In the drawings:—

Figure 1 is a face view of the advertising calendar.

45 Fig. 2 is a vertical section through the calendar casing from side to side and taken just back of the advertising card to disclose the adjustable webs and carrying means therefor.

50 Fig. 3 is a section on the line 3—3 of Fig. 2.

Fig. 4 is an extended face view of the web containing the names of the months.

Fig. 5 is a detail section on the line 5—5 of Fig. 1. 55

Referring to the drawings there is shown a casing 1 which may be and usually is of rectangular outline, although any particular shape is not obligatory. The frame 1 is formed on what may be termed the face 60 portion thereof with beads 2 forming shoulders 3 to receive and support a glass pane 4 behind which there is lodged a sheet 5 of cardboard or any other suitable material having a cut-away portion 6 for the display 65 of a portion of a web 7. The card 5 also has another cut-away portion 8 for the display of a portion of another web 9. There is still a third web, to be referred to, part of which is visible through the opening 6. Immediately 70 over the opening 6, considering the calendar as upright, there is a row 11 of indicia indicating in contracted form the names of the days of the week in a manner customary in calendars. While the opening 75 8 may be located in any desired relation to the opening 6, it is shown in the drawings as being above the opening 6 and above the indicia 11. The opening 8 is only large enough to display restricted areas of the 80 web 9, which latter may be in the form of a comparatively long strip divided into spaces 12, each of which contains the name of a calendar month and also information as to the number of days included in such 85 month. The names of the calendar months are contained on the strip 9 in regular order, but the name of one month only is displayed at the opening 8 at any one time. On opposite sides of the opening 8 and closely adjacent thereto the card 5 is formed with pairs of slits 13 to receive slips 14 with numbers thereon and capable of grouping to indicate the year date. 90

Contained within the frame 1 is another 95 frame 15 which may be made to snugly fit the frame 1. The frame 15 has longitudinal bars 16 near the top and bottom and these bars support a back 17 closing the frame 1 except between the bars 16 and the top and bottom of the frame 15. In this manner access may be had through the back of 100

the frame 1 to certain parts, while other parts are protected against access or damage. The frame 15 may be secured in the frame 1 in any suitable manner, the means of securing being of a removable nature, so that the frame 15 may be taken out of the frame 1 whenever desired. The frame 15 serves as a means for holding the glass pane 4 and card 5 in place, but by removing such fastening means as are employed to keep the frame 15 in place the latter may be taken from the frame 1 and the card 5 may be changed whenever desired. This is advantageous because the card is intended for advertising purposes, and hence the advertisements may be readily changed from time to time by taking out an old card and substituting a new one. The card 5 contains a suitable number of spaces 18 giving ample room for advertisements in close relation to the openings 6 and 8 and within the borders of the frame 1.

The bars 16 carry a suitable number of rotatable rods 19 which if the frames 1 and 15 be made of wood may also be made of wood. By making the rods cylindrical they may be turned upon their longitudinal axes in the bars 16 and by making them fit snugly in the bars and yet not too stiffly therein they may be readily turned by the fingers of an operator introduced in the spaces between the bars 16 and the top and bottom bars of the frame 15, these spaces being readily accessible as before stated.

In the particular arrangement shown six rods 19 are provided, there being three rods each on opposite sides of the openings 6 and 8. Behind these openings 6 and 8 the bars 16 carry a block 20 which may be of rectangular outline, and about as wide as or a little wider than the opening 6. At that end of the block 20 which constitutes the upper end in use the block is reduced in width to form a centralized projection 21 lengthwise of the block and reaching the upper bar 16, so that on each side of the projection there is an opening forming a shoulder 22 on the top of the block 20.

The rods or rollers 19 are located nearer to the back of the frame 15 than is the block 20, so that these rollers are sufficiently spaced back of the card 5 to be in non-interfering relation therewith. One set of rollers, say, those nearest to the block 20, have the ends of the web 9 fastened to and rolled upon them, so that on turning one of the rollers carrying the web 9, the latter is moved in one direction and on turning the other roller the web is moved in the other direction. The web 7 is wound upon the next pair of rollers 19 in order, these being the intermediate rollers of the sets of three. The web 7 contains series of numbers 23 arranged in longitudinal rows running from

top to bottom of the web, and so related that one end of the numbered part of the web 7, say, the right hand end, has the complete calendar for a month of thirty-one days where the first day of the month begins on Sunday. To the left of these numbers are other numbers in sufficient quantity and so arranged that by shifting the web 7 the numbers will be properly arranged for any month where the first day of the month begins on any other day than Sunday. The numbers are also so arranged and the opening 6 is of such size with respect to the groups of numbers that seven upright columns of numbers may be seen through the opening 6 at one time, while the lengthwise distribution and the arrangement of the numbers is such that thirty-one consecutive days may be made visible through the opening 6 at any one time. To bring this about the top row of numbers contains the digits 1 to 7, the second row of numbers contains the digits 2 to 14, the third row of numbers from 9 to 21, the fourth row from 16 to 28, the fifth row from 23 to 31, and there is also a sixth row containing the numbers 30 and 31 only. The web 7 is wound at the ends upon the intermediate rollers 19, whereby the web may be propelled in either direction.

There is also the third web indicated at 24 with step portions 25, 26, reducing the width of the web by amounts corresponding to the height of a longitudinal row of numbers 23. The web 24 is wound upon the terminal rollers 19 and the webs 7 and 24 are provided at certain points with the word "Stop" indicated at 27, or with some other indication of like import. These words are so positioned as to indicate to the operator where the web 7 is to be located for certain purposes. The web 24 is made to cover all the portions of the lower two longitudinal lines of numbers on the web 7, with the four longitudinal lines above the web 24 limited to twenty-eight different numbers, so as to serve for a twenty-eight day February.

Suppose that the calendar is to be set for the month of November, 1916. The operator by reaching into the casing 1 through the spaces at the back thereof is enabled to grasp those rollers 19 carrying the web 9 and by moving the proper ones of these rollers in the proper direction as is ascertained by observation of the web through the opening 8, the designation November is brought into sight and properly located. The designation is accompanied by a phrase indicating that November has thirty days. The numbers 1 9 1 6 are placed in the slits 13 of the card 5 before the latter is placed in the frame 1. Now, by reference to an ordinary calendar it is found that the first

of November, 1916, occurs on Wednesday, wherefore by a manipulation of the intermediate rollers 19 the web 16 is moved until the number 1 thereof is brought under the designation Wednesday on the day indicia indicated at 11. However, it will be seen by the arrangement of numbers on the web 7 that the number 31 will appear in the opening 16. To overcome this difficulty is the purpose of the web 24, so that the outer pair of rollers 19 is manipulated to bring the step portion 26 of the web 24 into covering relation to the number 31 previously visible through the opening 6.

The calendar is now set for the month of November, 1916, which month has thirty days. When December arrives the web 9 is correspondingly shifted and as December first occurs on Friday, the web 7 is also shifted. December is a thirty-one day month, and in the five superposed lines of numbers bearing on the web 7 the last visible number is 30, but the successive longitudinal row at the bottom of the other rows contains the number 31 in visible position with respect to the opening 6, but it is necessary to move the web 24 sufficiently to expose this number 31, wherefore the step portion 25 is propelled far enough to permit the visibility of the number 31.

So any one of the months may be displayed and the calendar may be set to be in proper relation thereto.

The calendar is of a perpetual nature, wherefore provision must be made for a twenty-eight day February and a twenty-nine day February. This is accomplished by having two spaces on the web 9 for the month of February, one of which is accompanied by a clause showing the month has twenty-eight days and the other with a clause showing it has twenty-nine days, and with a further clause stating that the month belongs to a leap year.

The invention is of a nature and the mechanical construction is such that it may be produced at a very low cost of manufacture permitting the use of the invention for advertising purposes and the gift of the device to those who will display it so as to make its advertising features of value to the advertisers.

The value of the advertisement is enhanced by the usefulness of the device as a calendar constraining those who would be benefited by observation of the calendar side of the device to read the advertisements and so become familiar with the articles advertised and thereby be led to purchase the articles or to patronize the advertisers.

What is claimed is:—

1. An advertising calendar structure, comprising a suitable frame or casing, a removable frame with adjustable calendar

members therein, and a removable and renewable advertising member adapted to be lodged in the casing and held therein by the removable frame, said advertising member having openings for viewing associated parts of the calendar members.

70

2. An advertising calendar comprising a frame, a glass pane adapted thereto, an advertising card also adapted to the frame to be lodged behind the glass, said card having openings therethrough and spaces about the openings for advertising purposes, and another frame adapted to be lodged in the first-named frame and carrying calendar members, said second frame clamping the advertising card and glass pane in place, and means for shifting the calendar members to bring chosen parts thereof into view through the openings in the advertising card.

3. A calendar structure comprising a suitable support with series of winding rollers therein, a web mounted on certain of the rollers and containing in series the names of the calendar months, another web mounted on certain others of the rollers and containing numbers in calendar arrangement, and a third web associated with the second web and mounted on certain others of the rollers and arranged to hide or display those parts of the second web constituting the lower parts in the installed position, said calendar being provided with a face member with openings therethrough arranged to display one month name at a time and sufficient of the numbers on the second web to include all the days of the displayed calendar month.

4. A calendar structure provided with an adjustable web having the names of the months thereon, another web having numbers corresponding to the number of days of the calendar month, and additional numbers of like character, a third web narrower than the second web and movable over what constitutes the lower portion of the second web in the installed position of the calendar to hide or display certain of the numbers on the second web, means for adjusting the webs, and covering means for the webs having openings therethrough for the display of so much of the first and second-named webs as shall correspond to a chosen calendar month.

5. A calendar structure provided with an adjustable web having the names of the months thereon, another web having numbers corresponding to the number of days of the calendar month, and additional numbers of like character, a third web movable to hide or display certain of the numbers on the second web, means for adjusting the webs, and covering means for the webs having openings therethrough for the display

125

120

115

in conjunction with the third web of only so much of the first and second named webs as shall correspond to a chosen calendar month, the covering member having means for the display of numbers representing the year.

In testimony, that I claim the foregoing as

my own, I have hereto affixed my signature in the presence of two witnesses.

GEORGE ALVAH N. COPPEDGE.
